FLEXIBLE STAYBOLT CONSTRUCTION
FOR BOILERSGarland P. Robinson, Glen Ridge, N. J., assignor
to American Locomotive Company, New York,
N. Y., a corporation of New York

Application September 28, 1935, Serial No. 42,580

7 Claims. (Cl. 85—1.5)

This invention relates to improvements in flexible staybolt constructions for boilers.

The object of the invention is to devise a flexible staybolt construction of a special but well-known type, hereinafter more particularly referred to, that is of simple, compact and comparatively cheap construction, is comparatively cheap in maintenance and sure in operation.

The type of staybolt construction to which the present invention applies is that in which the staybolt is known as the flexible tell-tale hole bolt having the tell-tale hole extending through the bolt longitudinally thereof and open at its outer or head end.

In the accompanying drawing Figure 1 is a central longitudinal sectional view of a staybolt construction embodying the present invention, secured to the boiler sheets fragmentally shown in section, the bolt being shown in elevation; Fig. 2 is an elevation of the staybolt assemblage; and Fig. 3 is a top plan view of the staybolt assemblage.

The tell-tale hole employed in staybolts is for the purpose of detecting defective bolts either while the boiler is in use or during times when the boiler is being tested for defective bolts. It is therefore essential that the tell-tale hole be maintained free from foreign matter and especially be free from foreign matter prior to a test. There are several well-known ways of testing the tell-tale hole to ascertain if it is satisfactorily open or free from foreign matter prior to making a boiler test, but where the tell-tale hole extends entirely throughout the bolt from end to end and is open at both ends it is comparatively easy to make this test for all that is necessary is to pass a wire from the inner end of the bolt through the hole to the outer end. It is this type of bolt that is employed in the present invention.

Describing now a preferred embodiment of the invention, a bolt assemblage, indicated generally by the reference character A, is shown in Fig. 1 as connected to the boiler in the usual manner. The assemblage comprises a sleeve 1 engaging a hole 2 formed in the outer plate 3 of the boiler and secured thereto by means of a weld 4. A seat 5 is formed on the inner wall of the sleeve and threads 6 are provided around the upper end of the outer face of the sleeve. The staybolt proper is denoted by the reference numeral 7. A spherical head 8 is formed on the outer end of the bolt 7, the head being disposed within the sleeve with its spherical surface engaging the seat in the usual manner to provide for the bolt a flexible connection with the sleeve. Threads

9 are provided on the opposite end of the bolt 7 and this end is screwed in a threaded orifice 10 provided in the inner boiler sheet 11, the inner end of the bolt being flanged over at 12 in the usual manner. The head end of the bolt is provided with diametrically disposed slots 13 for the application of a tool to facilitate screwing the bolt into the inner boiler sheet 11 in the usual manner.

As thus far described the staybolt construction is of ordinary design, and while the sleeve is shown as provided with a seat for receiving the bolt head, the invention is intended to cover structures wherein the seat is formed in the boiler plate and the sleeve is set upon the outer face of the boiler plate, as shown for instance in the reissue patent to Mennie, 14,796, Fig. 2 thereof. Furthermore, while a welded-on sleeve is shown, it will be understood that a threaded-on sleeve or any other appropriate sleeve may be used, if desired.

Cap 14 is secured to the sleeve 1, threads 15 being formed on the inner wall of the cap for this purpose, which are screwed upon the threads 6 formed on the sleeve, the cap being provided with a hexagonal outer surface 16 to facilitate screwing it upon the sleeve. The sleeve and cap provide a housing for the spherical bolt head. An opening 17 is provided in the cap and a plug 18 is secured in the opening. Preferably threads 19 are provided on the wall of the opening and threads 20 on the plug, as the means for securing the plug to the cap, the threads of the plug being screwed into the threads of the cap, and the plug having its outer end squared, as shown at 21, to facilitate screwing it into the cap.

The bolt 7 is provided with the usual tell-tale hole 22 open at the head or outer end, as indicated at 23, and at the inner end, as indicated at 24, where it communicates with the firebox in 40 the usual manner although the hole at this inner end may be temporarily closed, during service in the usual way if desired. A hole 25 extends longitudinally throughout the plug in line with the hole 22, and is open at its outer end to the exterior.

A diaphragm 26 is disposed across the housing, having its outer periphery secured to the wall of the housing and its central portion in engagement with the end of the bolt, this central portion being provided with an orifice 27 which affords communication between the holes 22 and 25. As shown in the preferred embodiment, the outer periphery of the diaphragm is disposed between the upper face of the sleeve and the lower

face of the cap, whereby by tightly screwing the cap upon the sleeve a seal is effected between the diaphragm and sleeve at the outer periphery of the former.

- 5 The plug 18 has its inner end pressing against the central portion of the diaphragm, thereby holding this portion tightly against the bolt in relative slidable engagement therewith. In the preferred embodiment this is accomplished by 10 screwing the plug sufficiently tight upon the diaphragm. Furthermore in the present preferred embodiment the end of the bolt at the head end thereof is formed spherically convex, as shown at 15 28, the center *x* of the sphere being preferably coincident with the center of the spherical head of the bolt. The diaphragm is formed cup-shape to provide a centrally disposed socket 29, the bottom of the socket (which is the central portion 20 of the diaphragm) being spherically shaped to correspond to the spherical shape 28 of the end of the bolt. The plug 18 has its inner end extending within the socket, the end wall thereof being spherically concave, as indicated at 30, complementary to the spherically convex surface 28. 25 The spherical joint thus provided between the diaphragm and bolt head permits of a rotatable slidable relative movement therebetween, although it will be appreciated that in actual practice this movement is very slight.
- 30 The plug may be screwed into the cap the required extent to produce the desired squeeze of the diaphragm between the plug and the bolt head. The cup-shape given the diaphragm enables the end of the plug to snugly fit the side 35 walls of the socket thus provided and to thereby best support the central portion of the diaphragm so that the bolt head may slide relative thereto in a practical manner under the maximum permissible pressure from the plug without unduly 40 pulling on the diaphragm at its outer periphery and without endangering the seal thereby. Furthermore, the angular shape given the diaphragm provides ample material in the diaphragm so that the plug may move the middle portion of the 45 diaphragm toward the bolt head to the desired extent without interfering with the seal at the periphery of the diaphragm. Furthermore, the diaphragm being backed up by the cap and plug throughout substantially its entire area, it is well 50 supported against any excessive pressure that might accumulate within the housing between the diaphragm and bolt head.

While the preferred design of diaphragm and plug have been shown and described, it will be 55 understood that it is not intended to thereby limit the scope of the invention, and other and variously shaped diaphragms and plugs may be employed that provide the required tight fit between the diaphragm and bolt head. Therefore it will be 60 understood that many and various changes and modifications in form, structure and arrangement of these parts as well as the various other parts of the construction may be made without departing from the spirit of the present invention, and 65 that all such changes and modifications are contemplated as a part of the present invention as defined by the appended claims.

The invention claimed and desired to be secured by Letters Patent is:

- 70 1. The combination of a boiler wall member; a housing member, one of said members having a seat, said housing member comprising a sleeve secured to said wall member and a cap secured to said sleeve and provided with an opening; a plug 75 secured in said opening, having a hole extending

therethrough open at the outer end to the exterior; a bolt having a head in flexible engagement with said seat and a longitudinal hole open at said head end; and a diaphragm extending across said housing with its outer periphery sealed to the wall of said housing, its central portion engaging said bolt and provided with an orifice affording communication between said holes, said plug having its inner end pressing against said diaphragm portion thereby holding 10 said portion tightly against said bolt in relative slidable engagement therewith. 15

2. A staybolt construction comprising a housing formed of a sleeve having a seat, and a cap, secured to the sleeve, having an opening; a bolt 15 having a head flexibly engaging said seat and a longitudinal hole open at the head end; a plug secured in said cap opening having a hole extending therethrough open at the outer end to the exterior; and a diaphragm extending across said 20 housing with its outer periphery sealed to the wall of said housing, its central portion engaging said bolt and provided with an orifice affording communication between said holes, said plug having its inner end pressing against said diaphragm 25 portion, thereby holding said portion tightly against said bolt in relative slidable engagement therewith.

3. A staybolt construction comprising a sleeve having a seat; a bolt having a head flexibly engaging said seat and a longitudinal hole open at the head end; a cap secured to said sleeve having an opening; a plug secured in said opening, having a hole extending therethrough open at the outer end to the exterior; and a diaphragm 35 extending across said sleeve with its outer periphery secured between said sleeve and said cap, its central portion engaging said bolt and provided with an orifice affording communication between said holes, said plug having its inner end 40 pressing against said diaphragm portion, thereby holding said portion tightly against said bolt in relative slidable engagement therewith.

4. A staybolt construction comprising a housing formed of a sleeve having a seat, and a cap, 45 secured to the sleeve, having an opening; a bolt having a head flexibly engaging said seat and a longitudinal hole open at the head end; a plug secured in said cap opening having a hole extending therethrough open at the outer end to 50 the exterior; and a diaphragm extending across said housing with its outer periphery sealed to the wall of said housing, its central portion cupped to form a socket having a bottom in engagement with said bolt and provided with an 55 orifice affording communication between said holes, said plug having its inner end extending into said socket pressing against said bottom, thereby holding said bottom tightly against said bolt in relative slidable engagement therewith. 60

5. A staybolt construction comprising a housing formed of a sleeve having a seat, and a cap, secured to the sleeve, having an opening; a bolt having a head flexibly engaging said seat and a longitudinal hole open at the head end, the end 65 of said bolt at said head end being spherically convex; a plug secured in said cap opening having a hole extending therethrough open at the outer end to the exterior; and a diaphragm extending across said housing with its outer periphery sealed to the wall of said housing, its central portion engaging said spherical end of said bolt, and spherically shaped correspondingly, and provided with an orifice affording communication between said holes, said plug having its inner 75

end concave complementary to said spherical end pressing against said diaphragm portion, thereby holding said portion tightly against said bolt in relative rotatable slidable engagement therewith.

5 6. A staybolt construction comprising a housing formed of a sleeve having a seat, and a cap, secured to the sleeve, having an opening; a bolt having a head flexibly engaging said seat and a longitudinal hole open at the head end, the end 10 of said bolt at said head end being spherically convex; a plug secured in said cap opening having a hole extending therethrough open at the outer end to the exterior; and a diaphragm extending across said housing with its outer periphery sealed to the wall of said housing, its central portion cupped to form a socket having a bottom in engagement with said spherical end of said bolt, and spherically shaped correspondingly, said bottom being provided with an orifice affording communication between said holes, said 15 plug having its inner end extending into said socket, concave complementary to said spherical end and pressing against said diaphragm portion, thereby holding said portion tightly against said bolt in relative rotatable slidable engagement therewith.

20

25

7. The combination of a boiler wall member; a housing member, one of said members having a spherically concave seat, said housing member comprising a sleeve secured to said wall member and a cap secured to said sleeve and provided with an opening; a bolt having a spherically convex head in flexible engagement with said seat and a longitudinal hole open at said head end, the end of said bolt at said head end being spherically convex, the centers of said spherical head and 10 said spherical end of said bolt coinciding; a plug secured in said cap opening, having a hole extending therethrough open at the outer end to the exterior; and a diaphragm extending across said housing with its outer periphery sealed to 15 the wall of said housing, its central portion engaging said spherical end of said bolt, and spherically shaped correspondingly, and provided with an orifice affording communication between said holes, said plug having its inner end concave 20 complementary to said spherical end pressing against said diaphragm portion thereby holding said portion tightly against said bolt in relative rotatable slidable engagement therewith.
